SPINDLE SLATS FOR COTTON HARVESTERS

John D. Rust, Memphis, Tenn.

Application March 29, 1944, Serial No. 528,586

12 Claims. (Cl. 56—42)

1

My invention relates to cotton picking machines of the kind disclosed in United States Patents No. Re. 19,411 issued January 1, 1935, No. 1,894-198 issued January 10, 1933, No. 2,058,513 issued October 27, 1936, No. 2,023,491 issued December 10, 1935, No. 2,058,514 issued October 27, 1936, No. 2,085,046 issued June 29, 1937, and No. 2,162,750 issued June 20, 1939.

The present invention has for its objects to provide spindle-carrying slats having a bearing at each side of the drive roller, the slats each being composed of snap-on elements that may be assembled without the use of screws or bolts; to provide improved quickly replaceable floating friction rails for driving the spindles; to provide an improved hinge for the spindle slats which will serve six purposes, namely, first, to pivot the slats, second to determine the angle of the spindles when in the picking position, third, to determine the stripping angle of the spindles, fourth, to act as a guide for the upper and lower spindle moistening rings, fifth, at least one of the hinges to carry a lug for actuating the moistening device, and sixth, the hinges are snapped onto the spindle-carrying slats and locked securely in place without the use of screws or bolts.

Other objects will in part be obvious and in part be pointed out hereinafter.

To the attainment of the aforesaid objects and ends, the invention also resides in the novel details of construction, combination, and arrangement of parts, all of which will be first fully described in the following detailed description, and then be particularly pointed out in the appended claims, reference being had to the accompanying drawings, in which:

Fig. 1 is a top plan view of a portion of a cotton picking machine embodying my invention, parts being broken away.

Fig. 2 is a top plan view on an enlarged scale of the backbone of one of the spindle-carrying slats.

Fig. 3 is a side elevation of a portion of a backbone.

Fig. 4 is a top plan view of one of the top and bottom ribs.

Fig. 5 is a side elevational view of the same.

Fig. 6 is a bottom plan view of the same.

Fig. 7 is a top plan view of one of the retainer clips.

Fig. 8 is a side elevation of the same.

Fig. 9 is a rear elevation of a portion of one of the slats and a hinge element attached.

Fig. 10 is a section on the line 10—10 of Fig. 9.

Fig. 11 is a cross-section on the line 11—11 of Fig. 10.

Fig. 12 is a side elevation of one of the intermediate ribs.

Fig. 13 is a front elevation of the same.

Fig. 14 is a bottom plan view of the same.

2

Fig. 15 is an enlarged detail view on the line 15—15 of Fig. 1 showing the spindle-carrying slat mounting at the position adjacent the spindle roughener and auxiliary doffer of my machine.

Figs. 2 to 11 are drawn to the same scale; Figs. 12, 13 and 14 are drawn on a different scale than Figs. 2 to 11 or Fig. 1.

Referring now to the accompanying drawings in which like numerals and letters of reference indicate like parts in all the figures, the main frame of the machine is composed of angle irons 1, 1^a, 1^b, 2 the drive shaft, 3 the driven shaft, 4 the conveyor chains, and 5 the spindle carrying slats.

15 Each slat comprises a sheet metal backbone 6 which includes a vertical face 6^a and two sides 6^b, the sides 6^b being recessed, as at 6^c, the edges 6^d being bent toward one another at angles of 45°. Ears 6^e are stamped from the recessed parts 6^c of at least one of the sides 6^b at suitable intervals to support the intermediate ribs of the slats, see Figs. 2 and 3. Top and bottom ribs as well as the intermediate ribs are clipped to the backbone 6 as will later more fully appear.

20 The space between opposite portions 6^b and the space between opposite portions 6^d of the backbone 6 constitute packing-strip-receiving channels.

25 The top and bottom ribs are of like construction and by reference to Figs. 4 to 11 inclusive it will be seen that these ribs 7 are each composed of sheet metal and comprise parallel side walls 7^a, 7^b joined by a rear wall 7^c. At the front the metal sides are inwardly offset as at 7^d and then doubled back upon themselves to form springy portions 7^e. The ends of the ribs 7 have inwardly bent portions 7^f, spaced above the cover portion 7^g of the rear reduced-in-width, bearing portion for the uppermost (or lowermost as the case may be) spindle. The spaces 8 serve as channels to receive the straps 9 later again referred to. The top and bottom ribs also include rear bearing-carrying portions 7^h with a back wall 7ⁱ and top and bottom closures 7^j and 7^k respectively (see Figs. 5 and 6). The space confined between the walls 7^b, 7^a, and 7^c and the space confined between the walls 7^h, 7ⁱ, 7^j, and 7^k of the top and bottom ribs 7 and the space confined between the walls 8^b and 8^a of the intermediate ribs, constitute bearing-block-receiving pockets.

30 The intermediate ribs 8 (see Figs. 9 to 14 inclusive) are of the same general form in cross section as the end or top and bottom ribs 7. They differ principally in that while the top and bottom ribs carry three spindles, the intermediate ribs support only two spindles each. Each intermediate rib comprises the sides 8^a, the back bearing carrier 8^b, 8^c, the sides 8^d, 8^e, the former being taller than the latter, see Fig. 12, and the 35 end or inner edge portions 8^f, 8^g.

When the ribs 7 and 8 are assembled to the backbone 6 the ribs are snapped over (clipped to) the backbone and the portions 7^c, 8^c snap into the recesses or channels 6^c and rest on the ears 6^e.

Wooden bearing blocks 14 are located in the back portions of the ribs (see Figs. 10 and 11) while long wooden bearing strips 10 extend the full length of the slat between the portions 7^c, 8^c of the sides of the ribs. Felt packing strips 11 and 12 are located at the front and back of the wooden strips 10 while felts 15 are located in front of the blocks 14. A fiber strip 13 lies against the outer side of the wall 6^a and fiber strips 16 lie against felt strips 15 which in turn lie against the blocks 14. The wooden strips 10 and the blocks 14 are bored to receive the spindles 18, the rollers 20 and collars 19 of which lie between the fiber strips 13 and 16, the felts 11, 12 and 15 being apertured accordingly.

After assembling the backbone 6 with its bearing strip 10, felts 11 and 12, the spindles 18 may be passed through the fiber strip 13, the felt 12, bearing strip 10 and felt 11. Then the fiber strips 16 may be put in place on the spindles and the ribs, with assembled bearing blocks 14 slipped on and snapped in place on the backbone, after which a retainer clip 9 is put on over the spindles. This clip comprises a full length channel member comprising a front wall 9^a side walls 9^b with bevelled portions 9^d to fit over the backbone and the rib portions 7^c, 7^d and 8^c, 8^d with retaining friction. Top and bottom straps 9^e having upturned ends 9^f are slipped over and under the upper and lower ribs respectively, as shown in Fig. 10.

In Fig. 15, I have shown a slat with its spindles in cooperative relation to the spindle roughener of my machine, a brief description of which will follow although I make no claim to the same as such roughener comprises the subject matter of my application filed September 24, 1945, Serial No. 618,105.

The spindle roughener includes a shaft 36 that carries a set of spaced rigid discs 41 to the under faces of which are secured abrasive rings 42. The discs 41 are spaced apart by suitable spacers 43 and secured by a nut 88 threaded on the shaft 38 so that the shaft and the discs with their abrasive rings comprise a unitary structure. The shaft 38 is bored at its lower end to set on a pin 39 carried by a bracket 40. The upper end of the shaft carries a swivel head 50 enclosing a suitable radial and thrust bearing (not shown, but well known) and having trunnions 50^a to rest in the bifurcated end of an arm 52 pivotally mounted at 53. An adjustable stop 54 limits the distance the arm may rise and hence limits the lift of the stack of abrasive unit. This unit is resiliently suspended by means of a lever 56 fulcrumed at 55 and held by a spring loaded bolt 58. The lever 56 has its free end inserted in an eye or loop 57 on the arm 52.

59 is a pipe, carried by the frame of the machine. On the pipe 59 is pivoted a rocker 60 one end of which presses on the swivel head 50 while the other end is pivoted to an eye bolt 61 threaded into the upper end of a tubular post 44 on the lower end of which post is a foot 45 which may ride up and down in a fixed guide 46. The post 45 carries suitably spaced pairs of rods 47 having pivot ends 47^a on which are carried shoes 48 that project between the abrasive disc elements 41, 42. When in non-operating position the shoes rest on top of the metal disc elements 41 leaving both the shoes 48 and the abrasive elements 42 75 clipped to the backbone; spindle mounting bear-

out of contact with the spindles 18. The shoes 48 have tapered front ends 48^a to cause the spindles to ride up over the arms 48 at all times. At the ends adjacent the post 44 guards 49 are secured on the shoes 48 to prevent cotton from being thrown over those ends and accumulating on the arms 47.

An operating arm 62 is secured to the pipe 59, to which the rocker 60 is also secured for the purpose of rocking the rocker 60 and thereby lowering abrasive unit's shaft 38 and raising the post 44, in consequence of which the spindles 18 will be held in contact with the abrasive. The arm 62 is operated by a piston 64 in a cylinder 63, the piston rod 65 being pivoted to the arm 62. Suitable operating fluid is admitted into the cylinder 63 from a suitable operator controlled source (not shown, but well known) via a pipe 66.

The shaft 38 is rotated step-by-step at suitable intervals by means of a pawl carrying-lever 68 pivoted on shaft 38 and having a pawl 69 to engage a ratchet 67 on the upper face of the top disc 41. The lever 68 has a pin 89 which lies in an elongated slot in a connecting rod 70 that is pivoted to the operating lever 35.

Referring now to Figs. 1 and 10, the improved spindle turning means will be understood. Secured to suitably located uprights 81 are horizontally disposed spaced-apart rail backing bars 76 curved as shown in Fig. 1. The friction rails are preferably formed of two channel irons 77 secured back to back and carrying in their channels the friction belts 78 and their resilient backings. The resilient backings may be of any approved structures, as for examples, pneumatic tubes 79^b, or resilient rubber 79^a as indicated in Fig. 10. The backing bars 76 at the rear ends have stops 80 against which the rear ends of the friction rails abut when in use. The backing bars 76 prevent the channel irons 77 and parts carried by the same from working out sidewise from between the spindle rollers. The bars 76 are not fastened to the channel irons.

In order to remove and replace the friction rails, the guard, fingers 82 on brackets 83, are removed, and a few slats and spindles are removed from the front whereupon the friction rails may be pulled out lengthwise (see dotted lines) and replaced by a reverse movement, when repairs are necessary. The bracket 83 is removably bolted to a vertical support 84 so as to be easily dismantled when necessary.

As the spindle conveyor is driven it will continuously tend to push the friction rails toward the back stops.

The hinge members 11 include portions 17^a having stop lugs 17^b and slots 17^c. The portions 17^a are passed from right to left through the end ribs below the parts 7^e and are held rigidly in place by keys 90 having locking tongues 91. The lugs 17^b abut one end of the rib portion 7^e while the end 92 engages the lug 9^e projected at right angles to the portion 9^c of the retaining clip 9.

From the foregoing description taken in connection with the accompanying drawings it is thought the construction, operation and advantages of the invention will be clear to those skilled in the art.

What I claim is:

1. In a cotton picking machine wherein spindle-carrying slats are mounted by means of hinge elements on conveyor chains: a slat unit comprising a sheet metal backbone; top and bottom ribs clipped to the backbone; intermediate ribs clipped to the backbone; spindle mounting bear-

ing elements carried by said backbone and said ribs; and spindles rotatably mounted in said bearing elements.

2. In a cotton picking machine wherein spindle-carrying slats are mounted by means of hinge elements on conveyor chains: a slat unit comprising a sheet metal backbone; top and bottom ribs clipped to the backbone; intermediate ribs clipped to the backbone; spindle mounting bearing elements carried by said backbone and said ribs; spindles rotatably mounted in said bearing elements; and a retaining clip held over said backbone and including means for holding the ribs to the backbone.

3. In a cotton picking machine wherein spindle-carrying slats are mounted by means of hinge elements on conveyor chains: a slat unit comprising a sheet metal backbone; top and bottom ribs clipped to the backbone; intermediate ribs clipped to the backbone; spindle mounting bearing elements carried by said backbone and said ribs; spindles rotatably mounted in said bearing elements; said backbone having longitudinally grooved sides and said ribs having portions to snap into the grooves of said sides; and a retaining clip held over said backbone and the portions of said ribs within said grooves.

4. In a cotton picking machine wherein spindle-carrying slats are mounted by means of hinge elements on conveyor chains: a slat unit comprising a sheet metal backbone; top and bottom ribs clipped to the backbone; intermediate ribs clipped to the backbone; spindle mounting bearing elements carried by said backbone and said ribs; spindles rotatably mounted in said bearing elements; and a retaining clip held over said backbone and including means for holding the ribs to the backbone; said top and bottom ribs having channelled portions and said retaining clip having straps projecting through said channelled portions; and means locking said straps in said channelled portions.

5. In a cotton picking machine wherein spindle-carrying slats are mounted by means of hinge elements on conveyor chains: a slat unit comprising a sheet metal backbone; top and bottom ribs clipped to the backbone; intermediate ribs clipped to the backbone; spindle mounting bearing elements carried by said backbone and said ribs; spindles rotatably mounted in said bearing elements; said backbone having longitudinally grooved sides and said ribs having portions to snap into the grooves of said sides; and a retaining clip held over said backbone and the portions of said ribs within said grooves; said top and bottom ribs having channelled portions and said retaining clip having straps projecting through said channelled portions; and means locking said straps in said channelled portions.

6. In a cotton picking machine wherein spindle-carrying slats are mounted by means of hinge elements on conveyor chains: a slat unit comprising a sheet metal backbone; top and bottom ribs clipped to the backbone; intermediate ribs clipped to the backbone; spindle mounting bearing elements carried by said backbone and said ribs; spindles rotatably mounted in said bearing elements; and a retaining clip held over said backbone and including means for holding the ribs to the backbone; said top and bottom ribs having channelled portions and said retaining clip having straps projecting through said channelled portions; hinge elements each having a leg located in said channelled portions and having a laterally offset leg apertured to receive a

link pin; and means for locking said hinge elements and said straps in the respective channelled portions of said top and bottom ribs.

7. In a cotton picking machine wherein spindle-carrying slats are mounted by means of hinge elements on conveyor chains: a slat unit comprising a sheet metal backbone; top and bottom ribs clipped to the backbone; intermediate ribs clipped to the backbone; spindle mounting bearing elements carried by said backbone and said ribs; spindles rotatably mounted in said bearing elements; said backbone having longitudinally grooved sides and said ribs having portions to snap into the grooves of said sides; and a retaining clip held over said backbone and the portions of said ribs within said grooves; said top and bottom ribs having channelled portions and said retaining clip having straps projecting through said channelled portions; hinge elements each having a leg located in said channelled portions and having a laterally offset leg apertured to receive a link pin; and means for locking said hinge elements and said straps in the respective channelled portions of said top and bottom ribs.

8. A spindle-carrying slat unit including a sheet metal backbone of generally U-shape in cross section and having bent in sides to constitute outer longitudinal channels, and provide inner longitudinal packing-strip-receiving channels spaced apart; a spindle bearing strip within the backbone; packing strips in said packing-strip-receiving channels at the front and back of said bearing strip; upper and lower end ribs and intermediate ribs each having elements to snap in said outer longitudinal channels for clipping the ribs to the backbone, said ribs having bearing-block-receiving pockets spaced from the backbone; bearing blocks in said pockets; and picking spindles, having rollers, mounted in said bearing blocks and penetrating said packing strips, said rollers being located between said backbone and the pockets of said ribs by virtue of which said spindles each have two bearings, one at each side of the roller.

9. A spindle-carrying slat unit including a sheet metal backbone of generally U-shape in cross section and having bent in sides to constitute outer longitudinal channels, and provide inner longitudinal packing-strip-receiving channels spaced apart; a spindle bearing strip within the backbone; packing strips in said packing-strip-receiving channels at the front and back of said bearing strip; upper and lower end ribs and intermediate ribs each having elements to snap in said outer longitudinal channels for clipping the ribs to the backbone, said ribs having bearing-block-receiving pockets spaced from the backbone; bearing blocks in said pockets; picking spindles, having rollers, mounted in said bearing blocks and penetrating said packing strips, said rollers being located between said backbone and the pockets of said ribs by virtue of which said spindles each have two bearings, one at each side of the roller; and a retaining clip held over said backbone and the portions of said ribs which lie in said outer longitudinal channels.

10. A spindle-carrying slat unit including a sheet metal backbone of generally U-shape in cross section and having bent in sides to constitute outer longitudinal channels, and provide inner longitudinal packing-strip-receiving channels spaced apart; a spindle bearing strip within the backbone; packing strips in said packing-strip-receiving channels at the front and back of said bearing strip; upper and lower end ribs and

intermediate ribs each having elements to snap in said outer longitudinal channels for clipping the ribs to the backbone, said ribs having bearing-block-receiving pockets spaced from the backbone; bearing blocks in said pockets; picking spindles, having roller, mounted in said bearing strips and penetrating said packing blocks, said rollers being located between said backbone and the pockets of said ribs by virtue of which said spindles each have two bearings, one at each side of the roller; and wear strips extending along the backbone and the ribs at each side of said roller to take the thrusts on the spindles.

11. A spindle-carrying slat unit including a sheet metal backbone of generally U-shape in cross section and having bent in sides to constitute outer longitudinal channels, and provide inner longitudinal packing-strip-receiving channels spaced apart; a spindle bearing strip within the backbone; packing strips in said packing-strip-receiving channels at the front and back of said bearing strip; upper and lower end ribs and intermediate ribs each having elements to snap in said outer longitudinal channels for clipping the ribs to the backbone, said ribs having bearing-block-receiving pockets spaced from the backbone; bearing blocks in said pockets; picking spindles, having rollers, mounted in said bearing blocks and penetrating said packing strips, said rollers being located between said backbone and the pockets of said ribs by virtue of which said spindles each have two bearings, one at each side of the roller; a retaining clip held over said backbone and the portions of said ribs which lie in said outer longitudinal channels; and wear strips extending along the backbone and the ribs at each side of said roller to take the thrusts on the spindles.

12. A spindle-carrying slat unit including a

sheet metal backbone of generally U-shape in cross section and having bent in sides to constitute outer longitudinal channels, and provide inner longitudinal packing-strip-receiving channels spaced apart; a spindle bearing strip within the backbone; packing strips in said packing-strip-receiving channels at the front and back of said bearing strip; upper and lower end ribs and intermediate ribs each having elements to snap in said outer longitudinal channels for clipping the ribs to the backbone, said ribs having bearing-block-receiving pockets spaced from the backbone; bearing blocks in said pockets; picking spindles, having rollers, mounted in said bearing-blocks and penetrating said packing strips, said rollers being located between said backbone and the pockets of said ribs by virtue of which said spindles each have two bearings, one at each side of the roller; said backbone having ears in at least one of its outer longitudinal channels by which ears said ribs are uniformly spaced apart along the backbone.
